(57) **CLAIM**

The ornamental design for a vacuum cleaner as shown and described.

DESCRIPTION

FIG. 1 is a front perspective view of a vacuum cleaner showing our new design;

FIG. 2 is a rear perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is an enlarged view of portion 9 shown in FIG. 1;

FIG. 10 is an enlarged view of portion 10 shown in FIG. 1; and,

FIG. 11 is a front perspective view shown in an environment of use with a holder.

The broken lines shown in FIGS. 1 to 10 depict portions of the vacuum cleaner that form no part of the claimed design. Other broken lines shown in FIG. 11 illustrate environmental structures that form no part of the claimed design. The long dash-short dash broken lines in FIGS. 1 and 9-10 define the bounds of the enlargements and form no part of the claimed design.
